[57] ABSTRACT

The eccentric flap valve is situated in an air intake of the carburetor upstream of the intake system for the primary air/fuel mixture, and actuated by the air flow against the effect of a first thermostatic member which tends to close it when the temperature of an element of the engine is below a given limit. A "fast idling" cam cooperates with a second thermostatic member, to partly open the usual throttle member of the carburetor when the flap valve is at least partially closed. Pneumatic means sensitive to the pressure which exists in the intake pipe downstream of the throttle member control the opening of the valve when the pressure diminishes. Stop means with several positions, limit, in variable manner as a function of the position that they occupy, the movement of the pneumatic means. Means sensitive to the ambient temperature control the position occupied by the stop means.

CARBURETTORS PROVIDED WITH A STARTING DEVICE WITH AN ECCENTRIC FLAP VALVE

The invention relates to carburettors of the type which comprise an eccentric flap valve starting device located in the air intake of the carburettor upstream of the system for the introduction of the primary air/fuel mixture, which valve is actuated by the air flow inspired by the carburettor against the effect of a first thermostatic member which tends to shut this valve when the temperature of an element of the engine is less than a given limit, said carburettor comprising in addition a cam called an "accelerated or fast idling" cam adapted to cooperate with a second thermostatic member, said cam being designed to partly open the usual throttle member of the carburettor when the starting valve is at least partially closed, pneumatic means sensitive to the pressure which exists in the intake pipe downstream of the throttle member being provided to control, by their movement, the opening of the flap valve when the abovesaid pressure diminishes.

Carburettors of this type have been described in our United States Patent Specification No. 3,185,453.

It is known that, soon after starting an engine which is still cold, it is necessary to partly open the flap valve so that the richness of the air-fuel mixture supplied to the engine is not too high. The role of the previously considered pneumatic means is, precisely, to partly open the flap valve.

The regulations relating to atmospheric pollution require the supply to the engine of mixtures whose richness is as low as possible, at least for temperatures in the neighbourhood of 20°C. However, for lower temperatures, it is necessary to supply to the engine, after starting, richer mixtures in order to avoid stalling.

In other words, the opening of the flap valve after starting, which conditions the richness of the air-fuel mixture, must depend on the ambient temperature at which the engine is started.

Devices are known which enable modification, as a function of the ambient temperature, of the pressure which actuates the pneumatic means connected to the flap valve, but these devices are of little accuracy since the position of the flap valve depends to a large extent on friction of the linking elements which actuate the flap valve.

It is a particular object of the invention to render carburettors of the type concerned such that they respond to the various exigencies of practice better than hitherto and especially such that they give a precise position of the flap valve after starting, which position must depend on the ambient temperature of starting and must be independent of the friction of the actuating elements of the flap valve.

According to the invention, a carburettor of the type defined above is characterised by the fact that it comprises stop means with several positions, adapted to limit in variable manner as a function of the position that they occupy, the movement of the pneumatic means, and means sensitive to ambient temperature adapted to control the position occupied by the stop means.

Preferably, these stop means with several positions are constituted by a stepped rotary cam, the various angular positions taken by the cam being controlled by means sensitive to the ambient temperature.

Advantageously, the stepped cam is constituted by a peripheral portion of the cam of "fast idling," different from the zone serving for the regulation of the opening of the usual throttle member; the means sensitive to ambient temperature are then constituted by the second thermostatic member of which one end is anchored at a fixed point and of which the other end is anchored on the "fast idling" cam.

The pneumatic means can be constituted by a diaphragm capsule connected to a rod of which the displacements control the opening of the flap valve; the rod comprises, advantageously, at its end distant from the diaphragm, a curved arm bearing an adjustable stop adapted to cooperate with the abovesaid stepped cam.

A preferred embodiment of the invention will now be described in more detailed manner with reference to the accompanying drawings.

FIG. 1 of these drawings shows diagrammatically, in elevation, with portions removed, a carburettor constructed according to the invention, and of which the elements occupy positions corresponding to the stopped engine and at ambient temperature.

FIG. 2 is a section along the line II-II of FIG. 1, of certain elements of the carburettor.

FIG. 3, lastly, shows similarly to FIG. 1, the carburettor with its elements in the positions which they occupy when the engine rotates at fast idling speed at an average temperature less than the normal temperature of operation of the engine.

As regards the carburettor as a whole, it is constituted essentially by a principal pipe 1 provided with an air intake 2 and with a conventional system for the introduction of the primary mixture (not shown).

As regards the starting device, it is constituted by an eccentric flap valve 3 mounted on an axle 4 upstream of the abovesaid system (the direction of flow is that indicated by the arrow of FIGS. 1 and 3) and actuated by the air flow sucked through the carburettor against the effect of a first thermostatic member 5 (shown in FIG. 2) constituted by a bimetallic spiral which tends to close the flap valve when the temperature of an element of the engine is less than a given limit.

The usual throttle member 6 of the carburettor is constituted by a butterfly valve mounted on an axle 7 downstream of the abovesaid system and actuated by the usual accelerated control (not shown) which, when it is released, tends to bring back the said throttle member to its minimum open position, this position being adjustable by a fast idling cam 8. To this end for example, this cam acts through steps 8a on an adjustable stop screw 10 borne by a lever 11, keyed on an axle 12 and connected through a linkage 13 to a lever 14 fast to the axle 7 of the butterfly valve 6.

The cam 8 is mounted freely on a fixed bush 15 (FIG. 2) on the inside of which an axle 16 passes freely. The bush 15 is driven into a case 17 which contains the thermostatic member 5; the case 17 is closed by a cap 18 of insulating material, which supports the member 5 and an electrical resistance 19 connected to the ignition circuit of the engine so as to cause heating of the member 5 as soon as the engine rotates.

At the end of the axle 16, situated in the case 17, is fixed a lever 20, well visible in FIG. 2, extending radially from one side to the other of the axle 16 and curved at its ends in the direction of the axle 16. The end 20a is curved towards the inside of the case 17 to

constitute a sort of finger around which is wound the movable end of the thermostatic element 5. This portion 20a will hence be drawn by the movable end of the element 5. The other end 20b of the lever 20 is curved in the opposite direction to the end 20a.

A lever 22 is fixed, by a nut 21, to the other end of the axle 16, spaced from the lever 20. The lever 22 is connected by a linkage 23 visible in FIGS. 1 and 3, to a lever 24 fast to the axle 4 of the valve 3.

The second thermostatic member 9 is constituted by a bi-metallic spiral wound around the bush 15, the central end of this spiral being made fast by anchoring to this bush and its opposite end 9a (FIGS. 1 and 3) being radially curved and wound around a pin 25 fast to the cam 8. This end 9a is hence anchored to the cam 8 and the second member 9 can drive the cam 8 either in clockwise direction or in the opposite direction.

This thermostatic member 9 is adjusted so that its end 9a moves in anticlockwise direction when it heats up.

The whole is arranged so that, when the thermostatic member 5 heats up, it causes rotation of the cam 8 in anticlockwise direction. To this end, a helical spring 26 (FIG. 2) is wound around the axle 16 between the bush 15 and the lever 22; one end 26a of this spring is curved in the direction of the axle 16 and housed in a hole 27 of the lever 22. The other end 26b of the spring 26 is constituted by a rectilinear part parallel to a radius of the cam 8, intended to cooperate with the pin 25 borne by this cam.

The lever 11, whose shape is clear from FIGS. 1 and 3, has one end 11a curved in a direction perpendicular to the plane of the whole of the lever 11. This end 11a is adapted to cooperate with a part 22a of the lever 22. The part 22a has the shape of an elbow oriented perpendicular to the average direction of the whole of the lever 22. Under these conditions, when the opening of the butterfly valve 6 is actuated, the lever 11 will turn in clockwise direction about the axle 12 and its end 11a will cooperate with the part 22a so that minimum opening is imposed on the valve 3.

The pneumatic means sensitive to the pressure which exists in the intake pipe 1 downstream of the butterfly valve 6, provided to actuate, by their movement, the opening of the valve 3 when the abovesaid pressure diminishes, are advantageously constituted by a capsule C (FIGS. 1 and 3) with a diaphragm 28. This diaphragm 28 separates the capsule into two chambers 29 and 30.

The chamber 29 is placed at atmospheric pressure, whilst the chamber 30 is connected through a passage (shown diagrammatically) to an orifice 31 opening into the pipe 1 downstream of the butterfly valve 6. The diaphragm 28 is gripped between two cups 32 and 33 and is coupled, through the latter, to a stem 34 extending parallel to a diameter of the casing 17 and passing through the latter into a groove g (FIG. 2) provided for this purpose.

Substantially at its middle portion, the stem 34 comprises a notch e bounded, on the side distant from the diaphragm 28, by an edge 34a, perpendicular to the longitudinal direction of the stem 34. The end 20b of the lever 20 becomes lodged in the notch e so that the edge 34a can cooperate with this end 20b.

A spring 35 arranged in the chamber 30 and supported on the one hand, against the bottom of this chamber and, on the other hand, on the cup 33, op-

poses the effect of the pressure on the diaphragm 28.

When the pressure at the level of the orifice 31 is sufficiently low, the diaphragm 28 moves towards the right from the position that it occupies in FIG. 1, to the position of FIG. 3, and the edge 34a of the stem 34 draws the end 20b so that the lever 22 turns in anticlockwise direction, which forces the valve 3 to partly open.

This being the case, according to the invention, there are provided stop means B (FIGS. 1 and 3) with several positions, adapted to limit, in variable manner as a function of the position that they occupy, the movement of the pneumatic means and more specifically, of the stem 34. There are also provided means T sensitive to ambient temperature, adapted to control the position occupied by the stop means B.

These stop means B are constituted preferably by a stepped rotary cam which is advantageously constituted by a peripheral portion p of the cam 8, different from the zone including the steps 8a serving for the adjustment of the opening of the butterfly valve 6. This zone p includes also steps 8b staggered angularly and such that, according to the position occupied by the cam 8, the limit imposed on the movement of the stem 34 varies.

The stop means B being constituted by a portion of the cam 8, the means T sensitive to ambient temperature are then constituted by the second thermostatic member 9 of which the end 9a is anchored on the pin 25.

The end 34b of the stem 34 is situated in a plane perpendicular to the longitudinal direction of the stem 34 as seen in FIG. 2. The stem end 34b bears a screw 36 serving as an adjustable stop adapted to cooperate with the steps 8b of the cam 8.

As a result of which, there is obtained a carburettor whose operation is as follows.

At low temperature, below 20° C, and before starting of the engine, the elements of the carburettor occupy the positions shown in FIG. 1. The cam 8 actuated by the thermostatic element 9 is in a position such that the screw 10 is in abutment on a step 8a which ensures wide opening of the butterfly valve 6. Simultaneously, the distance which separates the screw 36 from the steps 8b is slight so that, after starting of the engine, when the pressure in the chamber 30 tends to move the stem 34 towards the right in FIGS. 1 and 2, the stroke of this stem will be slight. In consequence, the end 20b drawn by the edge 34a will have a slight movement and the valve 3 will be little opened, thus ensuring a considerable enrichment of the air-fuel mixture admitted to the engine, necessary by reason of the low ambient temperature.

For an average ambient temperature of the order of 20° C for example, the element 9 imposes a position on the cam 8 (see FIG. 3) which is such that on the one hand, the butterfly valve 6 is further closed at idling than in the case of FIG. 1 and that, on the other hand, the screw 36 comes into abutment on a step 8b which is closer to the axle 16 than in the case of FIG. 1. As a result, the movement of the stem 34 under the action of low pressure existing at the orifice 31, is greater even than the rotation of the lever 22. It follows that the valve 3, after starting of the engine, is open more than in the case of FIG. 1, which gives a lesser enrichment than at low temperature but sufficient for the engine to turn normally.

It will hence be quite clear that the valve 3, after starting of the engine, takes a precise position which depends on the ambient temperature at starting and which is independent of the friction of the control elements of the valve.

As soon as the engine rotates, the electrical resistance 19 (FIG. 2), is heated and transmits heat to the element 5 which is deformed and then makes the axle 16 and the lever 22 rotate in anticlockwise direction. After sufficient rotation of this axle 16, the end 26b of the spring 26 drawn by the lever 22, engages with the pin 25; from this moment, it is the rotation of the axle 16 which controls the rotation of the cam 8 until the latter takes the position which corresponds to normal idling and to an opening of the butterfly valve 6 less than that which it had on starting. Simultaneously, the lever 22 by actuating the linkage 23 of the lever 24 fully opens the valve 3.

Thus, there is obtained a device which enables enrichment of the air-fuel mixture, at accelerated idling, which can be slight at ambient temperatures in the neighbourhood of 20° C, without however compromising sound operation at lower temperature since this enrichment is then greater.

I claim:

1. Carburettor comprising a starting device with an eccentric flap valve situated in an air intake of the carburettor upstream of an intake system for the primary air/fuel mixture, said valve being actuated by the air flow inspired by the carburettor against the effect of a first thermostatic member which tends to close said flap valve when the temperature of an element of the engine is below a given limit, said carburettor comprising in addition a cam called a "fast idling" cam adapted to cooperate with a second thermostatic member, said cam being intended to partly open the usual throttle member of the carburettor when the flap valve is at least partially closed, pneumatic means sensitive to the pressure in the intake pipe downstream of the throttle member being provided to control, by their movement, the opening of the valve when said pressure diminishes, said carburettor also comprising stop means with several positions, adapted to limit, in variable manner as a function of said position that they occupy, the movement of the pneumatic means, and said second thermostatic member constituting means sensitive to the ambient temperature arranged to control the position occupied by the stop means.

2. Carburettor according to claim 1, wherein said stop means are constituted by a stepped rotary cam, the

5 various angular positions taken by the cam being controlled by the ambient temperature sensitive means.

3. Carburettor according to claim 2, wherein the stepped cam is constituted by a peripheral part of the "fast idling" cam, different from the zone serving for the adjustment of the opening of the usual throttle member, the second thermostatic member having one end anchored at a fixed point and the other end anchored to the "fast idling" cam.

4. Carburettor according to claim 3, wherein the end of the second thermostatic member, which is anchored to the cam, is wound about a pin fast to the cam.

5. Carburettor according to claim 1, wherein the pneumatic means are constituted by a diaphragm capsule controlling the movements of a stem, and the stem comprises, at its end distant from the diaphragm, a curved arm bearing a screw constituting an adjustable stop, adapted to cooperate with the stop means in several positions.

6. Carburettor according to claim 5, wherein the stem comprises, in its middle part, a notch bounded by an edge, adapted to cooperate with the end of a lever controlling the opening of the flap valve, this lever being connected, at its other end, to the first thermostatic member.

7. Carburettor according to claim 6, wherein the lever connected to the first thermostatic member is keyed on the end of an axle rotating freely in a bush on which is mounted free in rotation the "fast idling" cam, the other end of the axle emerges from the bush and bears an arm connected to a linkage controlling the opening of the valve, the second thermostatic member being mounted about the end of the bush neighbouring said arm and the fixed end of said second thermostatic member being anchored in the bush.

8. Carburettor according to claim 7, wherein a helical spring is mounted around the axle between the arm and the neighbouring end of the bush, said spring being anchored, at one end in said arm and at its other end, comprising a rectilinear part arranged to cooperate, for a sufficient rotation of the arm, with a pin fast to the cam so that the latter is rotated by the arm.

9. Carburettor according to claim 2, wherein the pneumatic means are constituted by a diaphragm capsule controlling the movements of a stem, and the stem comprises, at its end distant from the diaphragm a curved arm bearing a screw constituting an adjustable stop, adapted to cooperate with the stop means in several positions.
